(57) **CLAIM**

The ornamental design for a sensor device, as shown and described.

DESCRIPTION

FIG. 1 is a front and side perspective view of a sensor device embodying our new design, where the sensor device includes a card and the card is detached from the sensor device;

FIG. 2 is a back and side perspective view thereof;

FIG. 3 is another front and side perspective view thereof;

FIG. 4 is yet another front and side perspective view thereof;

FIG. 5 is a front view thereof;

FIG. 6 is a back view thereof;

FIG. 7 is a right side view thereof;

FIG. 8 is a left side view thereof;

FIG. 9 is a bottom view thereof; and,

FIG. 10 is a top view thereof.

The broken lines illustrate portions of the sensor device that form no part of the claimed design.
